UNITED STATES PATENT OFFICE.

JOE DE GEORGE, OF ASHTABULA, OHIO.

DESIGN FOR A HAT HANGER.

Application filed September 6, 1928. Serial No. 28,057. Term of patent 14 years.

To all whom it may concern:

Be it known that I, JOE DE GEORGE, a citizen of the United States, residing in Ashtabula, in the county of Ashtabula and State of Ohio, have invented a new, original, and ornamental Design for a Hat Hanger, of which the following is a specification, reference being had to the accompanying drawing, forming part thereof, in which,

The ornamental design for a hat hanger, as shown.

JOE DE GEORGE.
